UNITED STATES PATENT OFFICE.

JOHN H. FLYNN, JR., OF CINCINNATI, OHIO.

RADIO APPARATUS.

Application filed May 6, 1926. Serial No. 107,201.

The invention relates to radio tuning apparatus.

The objects of the invention are to provide simple, efficient, durable, practical, economical and conveniently operative means adapted to tune or effect resonance in a radio circuit; and to provide means whereby the number of manual operative controls may be reduced, in certain phases of the tuning, thereby permitting 10 a greater number of stages of radio frequency amplification to be included especially, though not exclusively, in a "tuned radio frequency" radio circuit, without importantly complicating the manual operations required 15 to "tune" the circuit to the incoming signals.

The invention consists in the combination of the elements, arrangement of the parts and, further, in the details of the construction, as herein set forth and claimed.

20 In the drawings:

Fig. 1 is a plan view of a pair of variable condensers having the invention incorporated therein;

25 Fig. 2 is a section taken on a line corresponding to 2—2 in Fig. 1;

Fig. 3 is a side elevation of a condenser shaft;

30 Fig. 4 is a diagrammatical view of a radio circuit in which the invention is incorporated; and

Fig. 5 is a plan view showing a modified form of the invention, with parts broken away.

In the preferred construction of the invention as shown in Figs. 1 and 2 I provide front and rear variable condensers 1 and 2 each of which have rear and front supports 3 and 4, respectively, maintained in fixed spaced apart relation as by bolts 5 received through holes in the supports and insulator strips 6. Threaded in hole 7 in front support 4, as shown in Fig. 2, is tube 8 having nut 9 threaded to its outer protruding end 10. Tubular shaft 11 extending through tube 8, has its end 12 protruding through the front support of the condenser.

45 The rear reduced portion 13 of tubular shaft 11 is rotatably mounted in bearing 14 of tube 15 threaded in hole 16 in the rear support 3. The nut 17 is threaded to protruding end 18 of tube 15 and is screwed in close frictional contact with the outer side 19 of the rear support to maintain tube 15 in fixed position relative to the rear support.

50 The usual rotor plates 20 are secured in spaced apart relation on tubular metal shaft

11 by usual separators 21. The rotor plates are maintained against forward movement on tubular shaft 11 by flange 22 integral with the tubular shaft. Nut or ring 23, suitably fixed to the tubular shaft, bears in close frictional contact with rear rotor plate 24, whereby the rotor plates are maintained in fixed position.

55 The stator plates 25, as usual, are arranged in fixed relation on bolts 26 which are suitably fixed in insulators 6. The stator plates are disposed in spaced intermediate relation to the respective rotor plates, whereby rotation of tubular shaft 11 moves the rotor plates 70 parallel with the stator plates, thereby varying the capacity of the condenser.

55 As shown in Fig. 2, the end 12 of shaft 11, of front condenser 1, has usual manually operative dial 27 suitable fixed thereto by screw 28 for rotating shaft 11. The end 12 of shaft 11, of rear condenser 2, has end 29 of metal union 30 detachably secured thereto by screw 31.

60 Extending through union 30 and shafts 11, of front and rear condensers 1 and 2, and slideable therein, is metal rod or shaft 32 having manually operative dial 33 fixed by screw 34 to its protruding end 35 which extends through and forwardly of dial 27.

65 The dials 27 and 33 may be rotated independently of each other thereby permitting independent rotation of shaft 11 [of front condenser 1] and rod 32. When, however, it is desirable to rotate rod 32 and shaft 11 of the front condenser, the screw 36 in hole 37 in dial 33, may be screwed tightly in contact with dial 27, or irrespective of screw 36 the dials 27 and 33 may be gripped simultaneously by the operator to accomplish unison rotation of the dials. Other suitable and conveniently 90 operated mechanism may be employed to enable an operator to conveniently rotate the dials 27 and 33 in unison or independently of each other. For the purpose of permitting rotation of the rotor plates 20 of rear condenser 2 through normal operation of dial 33, the end 30' of the unison 30 is fixed by screw 38 to rod 32. By removing screw 31 from union 30, the rod 32 may be adjustably positioned with respect to shaft 11.

100 In Fig. 5, I show a modified form of the invention in which condenser 1 is utilized in conjunction with coil 39 consisting of usual primary and secondary windings 40 and 41 which are wound on tube 42. The primary 110 and secondary windings may be connected with the stator and rotor plates of the con-

densers by usual wires 43 and 44, shown broken away.

The support 45 suitably fixed to tube 42, is secured to shaft 46 by nut 46'. The shaft 46 fixed to union 30 by screw 31 corresponds to shaft 11, of condenser 2 shown in Figs. 1 and 2. The end 30' of union 30 is secured by screws 38, to shaft 32, whereby simultaneous rotation of the dials (not shown) 10 which may be fixed to shaft 11 of condenser 1 and rod 32, causes unison rotation of coil 39 and the rotor plates of the condenser, whereas as separate rotation of the dials may effect independent rotation of coil 39 and the rotor plates of the condenser.

It is apparent that various kinds of tuning apparatus may be arranged in combination with each other, by the use of the invention, whereby the various kinds of tuning appliances may be actuated in unison or independently of one another.

It is apparent that I have invented a highly desirable device for the purposes intended, and by the utilization of which multiple tuned 25 stages of "radio frequency" may be incorporated in a radio set having combined controls that are easily and conveniently operated. In the circuit 47 shown in Fig. 4, four variable condensers 1 and 2 are controllable by 30 two manually operated controls each of which may comprise dials 27 and 33 capable of being fixed to each other as shown in Figs. 1 and 2 for unison operation. When the circuit 47 is tuned to the highest efficiency of 35 results capable by unison operation of the condensers, the dials are turned separately whereby the volume of the incoming signals may be increased or reduced at the will of the operator. The condensers may be substituted 40 by variometers, variocouplers or other variable tuned transformers.

Under certain conditions as when the grid return leads are connected to -A 48 and +A 49, it may be desirable to establish an 45 insulation between condensers 1 and 2. This result may be effected by forming union 30 or shaft 32 from any suitable electricity non-conductive material, such as hard rubber, paper, glass or the like.

50 It is further apparent and I desire that it be fully understood that the invention may be made of any size and constructed of any materials deemed convenient, desirable and suitable for a device of this character, and 55 while I have described and shown in the drawings particular forms of the preferred constructions which I have found desirable in actually reducing the invention to practice, I desire to emphasize the fact that I 60 intend to include in this application all of the mechanical equivalents and substitutes that may fairly be considered to come within the scope and purview of the invention. For example, satisfactory results may be obtained by means of two variable condensers

arranged in tandem relation with each other and controllable in unison by a single dial, if usual compensating condensers, or miniature variable condensers, or compensating plates are utilized in combination with the 70 larger condensers.

What I claim as new and desire to secure by Letters Patent, is:

1. In a radio tuning apparatus, the combination with a pair of adjustable condensers, 75 each comprising relatively stationary plates and plates of the opposite polarity movable relative thereto, of an operating shaft for said movable plates electrically connected therewith for each of said condensers, a pair of 80 juxtaposed manually operative dials one of which is operatively connected with one of said shafts, a rod, detachable means for adjustably and operatively connecting said rod with the other of said shafts and said 85 rod being operatively connected with one of said dials, whereby said condensers are operated in unison and independently of each other.

2. A radio circuit tuning means, comprising 90 a pair of variable condensers and each having a shaft with rotor plates secured thereto, a rod, a means for adjustably securing the shaft of one of said condensers to said rod, and a pair of manually operative 95 dials respectively fixed to the shaft of one condenser and to said rod, whereby independent rotation of said dials effects a change in the capacity of said condensers independently of each other.

3. A radio tuning apparatus comprising a forward and a rearward condenser, each comprising relatively stationary plates and plates of the opposite polarity movable relative thereto, an operating shaft for each condenser for said movable plates electrically connected therewith, operating mechanism for said shafts and comprising a pair of dials capable of being rotated separately or in unison, one of which is fixed to one of said 110 shafts, a rod, a tubular union to fix said rod to the other of said tubular shafts, and one of said dials fixed to said rod.

4. In a radio tuning apparatus, a pair of independent tuning means each having a 115 movable part to effect tuning, a pair of shafts connected with said movable parts, respectively, a manually operative means connected with one of said shafts, a rod, a detachable union connecting said rod with the other 120 shaft, a second manually operative means adjacent said first mentioned manually operative means and operatively connected with said rod whereby simultaneous operation of said manually operative means is adapted to 125 actuate said tuning means in unison, and the independent operation of said manually operative means effects independent actuation of said tuning means.

JOHN H. FLYNN, JR.
